Primary Examiner — Selina Sikder(74) *Attorney, Agent, or Firm* — HOFFMANN AND BARON, LLP(57) **CLAIM**

The ornamental design for an operating element for a robotic exoskeleton, as shown and described.

DESCRIPTION

FIG. 1 is a top, front perspective view of the operating element for a robotic exoskeleton showing our new design;

FIG. 2 is a front elevation view thereof;

FIG. 3 is a right side elevation view thereof;

FIG. 4 is a back elevation view thereof;

FIG. 5 is a left side elevation view thereof;

FIG. 6 is a top plan view thereof; and,

FIG. 7 is a bottom plan view thereof.

The elements shown in broken line form no part of the claimed invention.
